UNITED STATES PATENT OFFICE.

JOHN V. BOLAND, OF ST. LOUIS, MISSOURI.

MOLD.

1,297,315.

Specification of Letters Patent. Patented Mar. 18, 1919.

Application filed October 1, 1917. Serial No. 194,157.

To all whom it may concern:

Be it known that I, JOHN V. BOLAND, a citizen of the United States, residing at the city of St. Louis and State of Missouri, have 5 invented a new and useful Mold, of which the following is a specification.

This invention relates to molds or forms of the type employed in the construction of concrete chimneys, silos and other similar 10 structures.

An object of the invention is to provide a mold or form for the construction of annular walls comprising a plurality of metallic plates secured together edgewise and capable 15 of being placed in annular form to provide the exterior mold for the wall, in combination with an inner mold, and means for retaining the exterior mold in proper position and relation to the inner mold, comprising a 20 series of rods connected to the exterior mold and passing through the inner mold and having connection with a strong retaining member within the inner mold.

Another object of the invention is to provide 25 an exterior mold for forming an annular wall comprising a series of metallic plates secured together edge to edge and capable of being placed in annular form, means for drawing the annular mold so formed into 30 proper adjustment, and a strong coöperating member within the mold having connections therewith whereby the mold is retained in a concentric form.

Another object of the invention is to provide 35 an improved mold constructed and operating as hereinbefore described and designed specially for use in construction of chimneys, silos and other structures of that general type.

40 In the accompanying drawings, in which my invention is illustrated,

Figure 1 is an open or diagrammatic view of the exterior mold before being placed in annular form.

45 Fig. 2 is a view of the mold in position for the formation of a section of a concrete structure for which the mold is designed.

Fig. 3 is a plan view of the mold and concrete structure shown in Fig. 2.

50 Fig. 4 is a vertical sectional view through the mold applied to a part of a chimney formed in the mold in a preceding position, the lower end of the mold engaging the upper portion of the finished part of the chim-

ney preparatory to being filled with concrete 55 to continue the chimney structure, the section of the mold being approximately on the line 4—4 of Fig. 3.

Fig. 5 is an enlarged detailed view of the connection by which the mold sections are 60 held together in edgewise arrangement.

Fig. 6 is an enlarged detailed view of the construction by which the mold is held together in annular form.

Fig. 7 is a view illustrating a modified or 65 alternative form of device for holding the mold in annular form.

The outer metallic mold is composed of a series of mold sections in the form of plates detachably secured together, edge to edge, 70 and of such form that when the connected plates are placed in annular form a tapering inclosure is formed. This is due to the fact that certain of the metallic plates are of slightly less width at their upper extremities 75 than at their lower extremities, while others may be of uniform width throughout their length, if desired. This construction of the plates will be readily apparent by reference to Fig. 1, in which it will be observed that 80 there is a central plate 1 which is of slightly less width at its upper end than at its lower end. Next, there are two series of plates 2 which are of uniform width throughout their length, the plates 2 of each series being connected together edgewise, and one of said series being connected to each edge of the plate 1; and to the edge of the last one of each series of the plates 2 there is connected 85 a plate 3 which is of slightly greater width 90 at its lower end than at its upper end. Next, there are two series of plates 4 of uniform width throughout their length, the plates 4 of each series being connected together edge- 95 wise, and one series of the plates 4 being connected to the outer edge of each of the plates 3.

The connection between each pair of edge- 100 wise abutting plates comprises a narrow plate 5 overlapping the adjacent or abutting edges of the plates 1, 2, 3 and 4 respectively, and secured thereto by releasable bolts 6 having their heads countersunk in the inner surfaces of the latter plates. The bolts 6 pass through the plates as stated and have detachable nuts 7 threaded on their outer ends for clamping the plates together as will be understood by reference to Fig. 5. The inner

surfaces of the heads of the bolts 6 are flush with the inner surfaces of the plates through which the bolts pass so that the bolt heads do not indent or otherwise disfigure the surface 5 of the concrete structure.

One method of securing the mold together in annular form is illustrated in Fig. 6, in which it will be seen that the plates 4 at the side of each series are overlapped. The 10 plates 4 are provided with vertical series of holes 8 which are so arranged that the holes in the overlapping plates register and receive bolts 9, the heads of which rest in countersunk holes in the inner plate. The 15 bolts 9 project entirely through the overlapping plates and are equipped with nuts so that the parts may be securely held together.

Another form of connection is illustrated 20 in Fig. 7. In this construction outwardly projecting angle plates 10 are secured near the upper and lower ends of the mold. As shown each of the plates 10 is composed of 25 two arms approximately at right angles to each other, one of the arms of each plate being bolted to the plates 5 nearest the edges of the mold structure, so that there are two of the plates near the lower end of the mold and two of the plates near the 30 upper end of the mold. The plates 10 at the upper and lower ends of the mold are provided with holes through which the connecting rods 11 extend, the ends of said rods being threaded and having nuts 12 thereon 35 so that the mold will thereby be held in annular form. When the mold is placed in annular form it tapers slightly from its lower end toward its upper end, so that the structure formed by the mold is gradually 40 tapering. Each of the rods 11 may be formed with a polygonal portion 13 for engagement by a wrench or the like, whereby the rods may be conveniently turned in order to release the nuts therefrom.

45 For coöperation with the connecting rods 11 it is desirable to employ a number of cables 14 to encircle the mold intermediate of the rods 11, said cables being equipped with stretchers 15 of any desired or usual 50 construction, whereby the cables may be drawn tight around the mold.

The inner mold is composed of the plates 16 arranged parallel with the plates of the outer mold. Certain of the plates 16 are 55 provided with brackets 17 which support the expanders 18. The expanders 18 are in the form of rods bent to annular form and seated in the brackets 17 so as to impart outward pressure against the plates 16. The expanders 18 are in the form of open rings, 60 since the ends of the rods of which the expanders are formed are not connected. This enables the expanders to adjust themselves to the varying diameters of the mold as the 65 height of the chimney increases.

The plates of the outer mold are provided with various holes 19 adapted to receive rods 20 which pass through said holes and similar holes or notches formed in the plates of the inner mold and seat within notches 70 formed in metallic rings 21 in the inner mold. Each of the rings 21 is composed of sections of angle iron as illustrated in Figs. 3 and 4., with one of the flanges extending outwardly, thus forming a strong connection for the rods 20 so that the outer mold will be rigidly retained in position concentric with the inner mold and the retaining rings. The section of the angle iron forming the rings 21 are connected by overlapping plates 22 and bolts 23 passing through the plates and the vertical angles of the sections. The bolts pass through slots 24 in the sections of angle iron, so that the rings may be made of varying diameters to conform to the tapering form of the chimney. 80 At the start it will be understood that the ends of the plates forming the rings 21 are spaced as shown in Figs. 3 and 4. Toward the top and narrow diameter of the chimney 90 the rings are contracted or reduced in diameter, the slots 24 permitting the bolts to assume different positions in connection with the angle iron sections.

In starting the construction of a chimney, 95 after the foundation has been made, the outer and inner molds are assembled in concentric relation by connecting the outer mold to several of the retaining angle iron rings. The space between the outer and inner molds 100 is then filled with concrete and after the concrete has set to a sufficient degree of hardness to retain its shape, the molds are released and the rods 20 are drawn out of the concrete. The molds are then raised to the 105 next higher stage, as illustrated in Fig. 4, and after being adjusted in proper position to form a continuous tapering structure, the space between the molds is again filled with concrete. In the second and subsequent positions of the mold, it is unnecessary to use more than one or two of the angle iron rings 110 near the top of the molds, since the cables encircling the outer mold are sufficient to retain the lower portion thereof in proper form. This operation is repeated until the structure has been erected to the proper altitude. After the molds are removed from each stage in the construction of the chimney, the holes in the concrete, left by the 115 withdrawal of the rods 20, are filled with concrete by use of a trowel or other appropriate implement, so that neither the interior nor the exterior surfaces of the structure discloses the positions in which 120 the rods were mounted.

From time to time during the erection of the structure one of the plates 4 is removed and the angular plates 10 are set over onto the next adjacent plate 4, so that the outer 130

mold is successfully reduced in size in order to meet the requirements for the erection of a continuously tapering structure.

For raising and lowering the exterior mold 5 angular plates 25 are secured to the exterior mold near the upper end thereof. Ropes or cables may be conveniently connected to the plates 25 and the mold may be thereby raised and lowered as required in the construction 10 of a building.

As illustrated the mold is applied to use in the construction of a concrete chimney, but it will be readily apparent that it may be used for the construction of any other 15 concrete structure of annular form. The exterior metallic mold forms a smooth and ornamental exterior surface and produces a structure which in practice has been found to be much superior to the structures produced by the usual molds composed of wood.

While I have illustrated the mold of tapering form it will be understood that it may be of any other desired shape. There may be other variations in the construction 25 and arrangement of the parts without departure from the scope of the invention.

What I claim and desire to secure by Letters Patent, is:—

1. A mold made up of a central tapering 30 section of flexible sheet metal; a series of sections of flexible sheet metal each of which is of uniform width from end to end, at each side of the central section; a tapering section of flexible sheet metal at the outer end 35 of each of said series of sections; and a series of sections of flexible sheet metal each of which is of uniform width throughout its length at the outer edge of each of the last-named tapering sections, the two end sections 40 of which are adapted to overlap when the mold is in annular form; whereby a tapering annular mold is formed, said last-named sections being removable one at a time, leaving an annular mold of the same 45 taper as the mold was before the section was removed.

2. A mold made up of a central tapering section of flexible sheet metal; a series of sections of flexible sheet metal each of which 50 is of uniform width from end to end, at each side of the central section; a tapering section of flexible sheet metal at the outer end of each of said series of sections; a series of sections of flexible sheet metal each of which 55 is of uniform width throughout its length at the outer edge of each of the last-named tapering sections, the two end sections of which are adapted to overlap when the mold is in annular form; whereby a tapering annular mold is formed, said last-named sections being removable one at a time, leaving 60

an annular mold of the same taper as the mold was before the section was removed; and plates overlapping and securing together the adjacent edges of all of the sections, respectively.

3. A mold made up of a central tapering section of flexible sheet metal; a series of sections of flexible sheet metal each of which is of uniform width from end to end, at each 65 side of the central section; a tapering section of flexible sheet metal at the outer end of each of said series of sections; a series of sections of flexible sheet metal each of which is of uniform width throughout its length 70 at the outer edge of each of the last-named tapering sections, the two end sections of which are adapted to overlap when the mold is in annular form; whereby a tapering annular mold is formed, said last-named sections being removable one at a time, leaving 75 an annular mold of the same taper as the mold was before the section was removed; plates overlapping and securing together the adjacent edges of all of the sections, respectively; and means for securing together the overlapping edges of the last-named series 80 of sections.

4. A mold composed of sheet metal, open at one side, means for holding the mold in 90 annular form, an inner mold concentric with the sheet metal mold, supports on the inner mold, devices supported by said supports for imparting outward pressure against the inner mold, a series of rings within the inner 95 mold out of contact therewith, and rods connecting the sheet metal mold with said rings and passing through the inner mold for holding the sheet metal mold rigidly in annular form.

5. A mold composed of sheet metal, open at one side, means for holding the mold in annular form, an inner mold concentric with the sheet metal mold, a series of supports on the inner mold, devices supported by said 105 supports for imparting outward pressure against the inner mold, and rods connecting the sheet metal mold and the inner mold, whereby each of said molds is supported in proper position relative to the other.

6. A mold composed of sheet metal, open at one side, means for holding the mold in annular form, an inner mold concentric with the sheet metal mold, a series of rings within the inner mold out of contact therewith, and 115 rods connecting the sheet metal mold with said rings and passing through the inner mold for supporting said two molds in proper position relative to each other and holding the sheet metal mold rigidly in annular form.

JOHN V. BOLAND.
